UNITED STATES PATENT OFFICE

153,873

DESIGN FOR A FLOOR LAMP BASE

Irving I. Gotliffe, New York, N. Y., assignor to
Remsen Lamp Manufacturing Co., Brooklyn,
N. Y., a partnership composed of Joseph Zweig
and Benjamin Zweig

Application November 10, 1947, Serial No. 142,443

Term of patent 3½ years

(Cl. D48—20)

To all whom it may concern:

Be it known that I, Irving I. Gotliffe, a citizen of the United States, residing at New York, in the county of New York and State of New York, have invented a new, original, and ornamental Design for a Floor Lamp Base, of which the following is a specification, reference being had to the accompanying drawings, forming a part thereof.

In the drawings:

Fig. 1 is a top plan view of a floor lamp base, showing my new design. The ornamentation of the portion shown in dotted lines is the same as the portion shown in full lines.

Fig. 2 is a view in side elevation thereof.

Fig. 3 is a fragmentary view taken along line 3—3 of Fig. 1.

I claim:

The ornamental design for a floor lamp base, as shown and described.

IRVING I. GOTLIFFE.
